PAUL GOFFART, OF BRUSSELS, BELGIUM, ASSIGNOR, BY MESNE ASSIGNMENTS, TO
BELGIAN AMERICAN COKE OVENS CORPORATION, OF WILMINGTON, DELAWARE,
A CORPORATION OF DELAWARE.

COKE OVEN.

Application filed April 8, 1920. Serial No. 372,111.

To all whom it may concern:

Be it known that I, PAUL GOFFART, a subject of the King of Belgium, and resident of Brussels, Belgium, have invented 5 certain new and useful Improvements in Coke Ovens, of which the following is a specification.

This invention relates to coke ovens with regeneration of heat by periodical reversal 10 of the draft.

In a certain well known type of coke ovens of this character, with recovery of by-products, the regenerator checker brick for heating the air during one stage is 15 placed in two chambers having arched roofs located under the coking chambers, said regenerator chambers extending at one side of the axis of the bench of coking chambers and parallel to said axis. The 20 said regenerator chambers are connected in series by means of a plurality of conduits increasing in cross section progressively according to their distance from the chimney. A similar arrangement of connected regenerator chambers provided on 25 the other side of said axis, serves to heat the air during the other stage. The combustion products pass first through one of the regenerator chambers, termed the primary chamber, and after being partially 30 cooled therein, pass upwardly through the checkerwork in the other (secondary) regenerator chamber and escape to the chimney. In this well known type of coke ovens, the same regenerators serve for all 35 the coking chambers of a bench.

In certain cases it may be desirable to provide individual regenerators for each coking chamber. The object of the present 40 invention is to provide regenerators of the general character referred to above, but with each coking chamber having its individual regenerators connected in series. For this purpose, partitions divide the regenerators of the former constructions into individual groups of regenerator compartments, each group connected to a single sole channel. In order that the flow of 45 gases (or air) may be in the same direction in one of these compartments as in the compartment connected therewith, the lower portion of one primary compartment is connected, by a vertical conduit, with the

upper portion of the companion secondary compartment.

Rich heating gas may be employed with 55 this arrangement. Furthermore, it is also possible to heat with poor gas, by connecting the sole channel of each coking chamber with the two heating walls at the sides 60 of said chamber, and feeding air through alternate regenerators while the intervening regenerators receive the poor gas. By 65 a simple manipulation of cocks or valves, the operation may be changed from one heating system (rich gas) to the other (poor gas).

A typical example of this invention is 70 illustrated by the accompanying drawings, in which Fig. 1 shows the improved coke oven in longitudinal vertical section, the left hand portion on the line A—B of Fig. 2, and the right hand portion on the line A'—B' of said figure, which is a cross section on the line 2—2 of Fig. 1; Figs. 3 75 and 4 are partial horizontal sections, at opposite ends of the oven, taken on the plane indicated by the line 3—3 of Fig. 1.

Reference letters or numerals without indices are used to designate parts on one side 80 of the longitudinal center or axis of the bench, and like reference letters or numerals with indices designate the corresponding parts on the opposite side of the bench.

On each side of the coking chambers 1 85 are located heating walls each containing a plurality of upright flues 2 (or 2') communicating by gas nozzles 3 (or 3') with gas chambers 4 (or 4') placed directly below them, each of said gas chambers supplying several nozzles, and receiving coke oven gas through pipes m (or m') provided with individual regulating valves indicated in Fig. 1. The gas chambers along one half of a heating wall are connected with the pipes m , and those along the other half, with the pipes m' . From the lower end of each heating flue 2, ducts 5 extend downwardly and to both sides, connecting with sole channels 6 located directly under the coking chambers 1 and it will be understood 90 that similar ducts and sole channels are provided in connection with the flues 2'. These channels 6 extend from each side of the bench (from left and right in Fig. 1) 95 to the longitudinal center of the bench, the

channels at one side of said center being separated from those at the other side, by partitions 8 extending lengthwise of the bench (that is to say, transversely of the 5 coking chambers). In the arrangement adopted to enable the oven to be heated with poor gas, each sole channel 6 is divided into two longitudinal passages by a central vertical partition 13. Furthermore, 10 each of these sole channels is also provided with a horizontal partition 7, extending from the partition 8 to a short distance from the outside wall of the oven, the ducts 5 opening into the channels 6 above 15 said partition 7, while at a point below said partition 7 and adjacent to the partition 8, each channel 6 is connected, as indicated at 9, with that compartment of the primary regenerator *a* (or *a'*) which is directly beneath that particular sole channel and coking chamber. The flow of gases through the channels 6 may be regulated by means 20 of slides or dampers 10, there being an independent damper for each channel. 25 The primary regenerators *a*, *a'*, and the secondary regenerators *b*, *b'*, extend transversely of the sole channels 6, that is to say, lengthwise of the bench of coke ovens. By means of partitions 11, 11', the primary regenerators are divided into as many separate compartments as there are coking chambers 1, and by means of corresponding partitions 12, 12', the secondary regenerators are divided similarly into unconnected compartments, 30 each compartment of a primary regenerator being connected to the corresponding compartment of the adjacent secondary regenerator as follows: A set of horizontal channels *c* (or *c'*) extends from the bottom of each compartment of a primary regenerator *a* (or *a'*) to the lower end of an upright channel *g* (or *g'*) located adjacent to the companion compartment of the adjacent secondary regenerator *b* (or *b'*), 35 the upper end of said upright channel *g* (or *g'*) communicating, above the checkerwork, with such companion secondary regenerator compartment. Below such checkerwork, each compartment of the secondary regenerator *b* is connected by a channel *h* with a waste flue or stack flue *D*, and similarly located channels *h'* connect the individual compartment of the other secondary regenerator *b'* with a corresponding stack flue 40 *D'* on the other side of the oven. Alternate channels *h* are provided with valves or dampers *f* (the intervening channels *h* being without dampers), and a similar arrangement of dampers *f'* is employed in 45 connection with the corresponding channels *h'* on the other side of the oven. The channels having such dampers are provided with nozzles connected with pipes having valves *n*, *n'*, respectively and receiving poor gas 50 (producer gas) from suitable mains.

The stack flues *D*, *D'*, the main portions of which extend lengthwise of the bench of coke ovens, have their connection with the chimney *O* and with the air-supply channel 14 controlled by a reversing valve *V* which 70 in the example shown is adapted to swing about a vertical axis. The draft in each of the flues *D*, *D'*, may be regulated by a valve or damper *r*, *r'*, respectively.

Let us assume that the fuel employed is 75 coke oven gas and that at a certain stage combustion is to take place in the heating flues of the left hand half shown in Fig. 1. The reversing valve *V* is placed in the position indicated by full lines in Fig. 4, so that 80 air from the channel 14 will pass to the flue *D*, while the companion flue *D'* communicates with the chimney *O* to discharge into the same. The valves *f*, *f'* are open, the valves *n*, *n'*, for the admission of producer 85 gas are closed, the burner pipes or nozzles *m* are open, and the companion pipes or nozzles *m'* are closed. Air for supporting combustion passes from the flue *D* and the channels *h* into the respective compartments 90 of the secondary regenerator *b*, and thence through the channels *g* and *c* into the corresponding compartments of the primary regenerator *a*, and in both of these regenerators the air is heated by contact with the 95 checkerwork heated during the preceding stage of the operation. From the compartments of the regenerator *a* the heated air rises through the ducts 9 into the lower compartments of the sole channels 6, and 100 passes to the upper compartments of said channels and through the ducts 5 into the flues 2 located in the heating walls of the coking chambers 1 disposed directly above the respective sole channels 6. Coke oven 105 gas is admitted to the gas chambers 4 through the pipes *m* and passes through the nozzles 3 into the heating flues 2, in which it meets the heated air admitted from the sole channels 6 through the ducts 5. 110

Combustion takes place in the heating flues 2, and the combustion gases pass upwardly through openings 16 of proper cross section, into the horizontal upper channels 15, 15' in which they travel toward the other half of the oven, that is, the half containing the heating flues 2'. Into these latter flues the combustion gases enter through the openings 16', and traveling downwardly they leave these flues 2' through ducts 115 similar to the ducts 5, thus reaching the sole channels (similar to the channels 6), on the side of the oven having the flues 2', and from these sole channels the combustion gases pass successively to the primary regenerator *a'*, to secondary regenerator *b'*, and the flue *D'* to the chimney *O*, through a path which while not fully shown in the drawing, so far as this half of the oven is concerned, will be readily understood since 120 125 130

it corresponds exactly to the path 6, 9, a, c, g, b, h, D, of the other half of the oven. During this stage, therefore, the checkerwork in the regenerators a', b', absorbs heat.

5 When these regenerators have reached the proper temperature, the next stage is started by reversing the air and gas currents as follows:

The valve V is shifted to the position indicated by dotted lines in Fig. 4. This will cause air from the supply channel 14 to now pass to the flue D', regenerators b', a', the sole channels and ducts located above these regenerators, and the heating flues 2'. 10 The burner pipes or nozzles m are closed during this stage, and the burner pipes or nozzles m' open to admit coke oven gas to the chambers 4', gas nozzles 3', and heating flues 2'. The combustion gases travel upward 15 in these flues and pass through the openings 16' to the top channels 15', 15, and out through the flues 2 downwardly, ducts 5, sole channels 6, ducts 9, regenerator a, channels c, g, secondary regenerator b, 20 channels h, the flue D and the chimney O. During this stage, therefore, the regenerators a, b, store up heat.

If the coke oven is to be operated with producer gas, the burner pipes or nozzles m, 30 m', are closed, as are also the valves f' controlling the connection of alternate compartments of the generator b' with the flue D', the corresponding valves f on the other half of the oven bench are opened, the reversing valve V is placed in the position indicated by dotted lines in Fig. 4, the valves n are closed, and the valves n' opened. At this stage, air will be heated by passing through those (alternate) compartments of 35 the regenerators b' and a' which have no controlling valves f', while the producer gas will pass through the other compartments of said regenerators b' and a', that is to say, through the (alternate) compartments, the connection of which with the flue D' is at that time closed by the valves f'. The air and gas thus preheated will enter the heating flues 2' at the bottom, and the combustion gases traveling upward in said 40 flues will pass out through the same path as described above. During the next stage, the valves f will be closed, the corresponding valves f' on the other half of the oven will be opened, the reversing valve V is 45 placed in the position indicated by full lines in Fig. 4, the valves n' are closed, and the valves n opened. Air to be heated will now pass to those (alternate) compartments of the regenerators b and a which have their 50 connection with the flue D open permanently, while the producer gas to be heated will pass through the other (alternate) compartments of said regenerators b and a, that is, those compartments which at that time 55 are closed to the flue D by the valve f. In

this case air and gas will meet at the lower portions of the heating flues 2, and the combustion products will pass out from the upper portions of these flues through the same path as described above.

It will be obvious that when both modes of heating (producer gas and coke oven gas) are to be combined, all that will be necessary is to admit coke oven gas on the same side as the poor gas (producer gas or blast furnace gas), the procedure, otherwise, being the same as when heating with poor gas, as described above.

It will be noted that the hot combustion gases travel downwardly in the checker-work of all the regenerators, and this is of great importance as any upward flow of hot gases through checkerwork would be retarded by the cooling effect since cool gas tends to sink. The channels g, being unobstructed by checkerwork, avoid such detrimental cooling of the hot gas during its upward travel. Similarly, when gas or air is sent through the regenerators to take up heat therefrom, such gas or air will travel upwardly through the checkerwork, so that the effect of the heat will assist the upward flow through the checkerwork, while in the channels g through which such gas or air travels downwardly, there is no checker-work to produce a strong heating effect which would impede such downward flow.

I claim:

1. In a longitudinal coke oven bench having upright heating flues operating with reversal of the draft, companion regenerators disposed lengthwise of the bench and transversely under the sole of the coking chambers, said regenerators being partitioned to form separate compartments corresponding to the individual coking chambers, and external smoke flues for connecting said regenerator compartments with a stack, each compartment of one of the companion regenerators having its lower portion connected by a substantially unobstructed upright channel with the upper portion of the corresponding compartment of the other regenerator, whereby the current of fluids will be caused to travel in the same direction in both of such connected compartments.

2. In a coke oven having a plurality of coking chambers and heating flues therefor, companion regenerators, one connected at one of its horizontal terminations with said flues and each partitioned to form separate compartments each corresponding to a single coking chamber, each compartment of one of said companion regenerators having its lower portion connected by a substantially unobstructed upright channel with the upper portion of the corresponding compartment of the other regenerator, whereby the current of fluids will be caused to travel

in the same direction in both of said connected compartments, and connections from the other horizontal terminations of the compartments of the other of said regenerators 5 to a stack and to an air-supply.

3. A coke oven having heating flues and companion regenerators one connected at one of its horizontal terminations with said flues, connections from the other of its horizontal terminations of the other regenerator to a stack and to an air-supply, and a substantially unobstructed upright channel connecting the upper portion of one regenerator with the lower portion of the other, 15 whereby the current of fluids will be caused to travel in the same direction in both of said connected regenerators.

4. In a longitudinal coke oven bench having upright heating flues operating with reversal of the draft, companion regenerators disposed lengthwise of the bench and transversely under the sole of the coking chambers, said regenerators being partitioned to form separate compartments corresponding 20 to the individual coking chambers, and external smoke flues for connecting said regenerator compartments with a stack, each com- 25

partment of one of the companion regenerators having its lower portion connected by a substantially unobstructed upright channel 30 with the upper portion of the corresponding compartment of the other regenerator, whereby the current of fluids will be caused to travel in the same direction in both of such connected compartments, sole channels each of 35 which is connected with heating flues on opposite sides of the same coking chamber, and with one compartment of one of said regenerators, so that the heating flues at the same side of a coking chamber are connected 40 with two adjacent regenerator compartments, means whereby either all of the regenerator compartments may serve to heat air for the combustion of rich gas, or only alternate regenerator compartments may be 45 used to heat air, while the intervening regenerator compartments serve to heat poor gas to be burnt with said air, and valves for effecting the change from one system of heating to the other. 50

In testimony whereof I have hereunto set my hand.

P. GOFFART.
